UNITED STATES PATENT OFFICE

104,584

DESIGN FOR A STOPPER FOR PERFUME BOTTLES AND THE LIKE

Louis Albert Samstag, New York, N. Y.

Application April 9, 1937, Serial No. 68,645

Term of patent 3½ years

To all whom it may concern:

Be it known that I, Louis Albert Samstag, a citizen of the United States, residing in New York, county and State of New York, have invented a new, original, and ornamental Design for a Stopper for Perfume Bottles and the like, of which the following is a specification, reference being had to the accompanying drawing, forming part thereof.

I claim:

The ornamental design for a stopper for perfume bottles and the like, as shown.

LOUIS ALBERT SAMSTAG.
